LOUIS W. BOSART, OF STE. MARIE, ILLINOIS.

Letters Patent No. 76,151, dated March 31, 1868.

IMPROVEMENT IN PORTABLE WIRE FENCES.

The Schedule referred to in these Letters Patent and making part of the same.

TO ALL WHOM IT MAY CONCERN:

Be it known that I, Louis W. Bosart, of Ste. Marie, in the county of Jasper, and State of Illinois, have invented a new and useful Improvement in Portable Wire Fences; and I do hereby declare that the following is a full, clear, and exact description of the same, reference being had to the annexed drawings, making part of this specification.

A is a frame for supporting the capstans B, which turn on a rod, B¹, passing through the upper and lower parts of the frame. These capstans are independent of one another, and each may be operated without moving the others. The frame is supported by trestles, A¹, as shown. The vertical end-pieces A² are bored with holes corresponding in position to the number and spaces of the wires to be used. The wires C C are attached to one of the corner-pieces D in building the fence, and thence extended through a series of trestles formed like them, but lighter, and resting on the ground. The corner-trestles have the vertical piece extended, to be set in the ground, so as to resist the strain of the wires. In the middle of the side of the fence are placed the frame A and capstans B. The shaft of each capstan is bored with a hole corresponding with the position of the wire intended to pass through it. The wires are then extended to the other corner-post, passing through intermediate trestles. Strips are suspended midway between the trestles from the top board F, through which the wires pass. The top boards F are fastened on the trestles and posts by means of the wires F'. The upper ends of the vertical posts of the trestles are notched, to receive the board F, and the ends of the boards are shouldered, so as to resist the lateral movement of the trestles, and hold them in position.

When any of the wires require to be slackened or tightened, it may be done by turning the capstan, through which it is passed. This may be done by the radial arms B². These arms may be held in position by wires, B³, fastening them to the frame-posts A², so as to prevent the capstan's turning to relax the wire. Any equivalent device, as a ratchet and pawl, may be used for this purpose.

When the fence is to be taken down, the ends of the wires being detached, the wires may be respectively wound upon their own capstans, and the boards F, trestles, and strips E, taken apart. In resetting the fence, the wires are transported in coils on the axle of the capstans; and, these being placed in the frame A, the wires may be unwound and passed, through the intermediate trestles and strips E, to the corner-posts D.

What I claim as my invention, and desire to secure by Letters Patent, is—

1. In combination with the wires C, a corresponding number of capstans, B, through the shafts of which the wires pass, and around which they may be wound, substantially as and for the purpose set forth.
2. The combination of the wires C, corner-posts D, intermediate triangular trestles, boards F, and strips E, constructed and arranged substantially as described.
3. The combination of the frame A, capstans B, wires C, and posts D, arranged substantially as described.

In testimony whereof, I have signed my name to this specification in the presence of two subscribing witnesses.

L. W. BOSART.
